UNITED STATES PATENT OFFICE.

CHARLES LEVIN, OF NEW YORK, N. Y.

DESIGN FOR A CUT-GLASS DISH.

48,117.

Specification for Design.

Patented Nov. 9, 1915.

Application filed April 20, 1915. Serial No. 22,703. Term of patent 3½ years.

To all whom it may concern:

Be it known that I, CHARLES LEVIN, a citizen of the United States, and a resident of the city of New York, borough of the Bronx, in the county of Bronx and State of New York, have invented a new, original, and ornamental Design for a Cut-Glass Dish, of which the following is a specification, reference being had to the accompanying drawings, which form a part thereof.

The figure is a plan view of a dish showing the new design.

I claim:

The design for a cut-glass dish, as shown.

CHARLES LEVIN.

Witnesses:

E. F. MURDOCK,
PHILIP D. ROLLHAUS.
